UNITED STATES PATENT OFFICE.

FRANCIS X. LIST, OF NEW YORK, N. Y., ASSIGNOR TO NATIONAL CARD MOUNTING COMPANY, OF NEW YORK, N. Y., A CORPORATION OF NEW YORK.

DISPLAY-FOLDER.

1,396,224.

Specification of Letters Patent.

Patented Nov. 8, 1921.

Application filed March 5, 1921. Serial No. 449,702.

To all whom it may concern:

Be it known that I, FRANCIS X. LIST, a citizen of the United States, and resident of the borough of Bronx, city and State of New York, have invented certain new and useful Improvements in Display-Folders, of which the following is a specification.

This invention relates to improvements in display folders, such as consist of a plurality of flexibly connected sections, which are adapted to be arranged in an upright position and display an advertisement printed on one of their faces.

The general object of the invention is the provision of a connection constructed so as to give an appearance of continuity to the display surface of the folder made up of the display surfaces of the sections thereof when the folder is set upright in display position; and further constructed to permit of frequent folding and unfolding of the sections without impairing the connection and thereby rendering the folder useless.

To these ends, the invention resides in uniting oppositely disposed marginal portions of the intermediate section of the folder with marginal portions of the side or wing sections superimposed thereon and providing the said side or wing sections with crease hinges.

Other objects will appear and be better understood from that embodiment of the invention of which the following is a specification reference being had to the accompanying drawings forming a part thereof, and in which:

Figure 1 is an elevation of the device in folded position;

Fig. 2 is a cross section on line 2—2 of Fig. 1;

Fig. 3 is a view similar to Fig. 1 showing the parts in display position;

Fig. 4, is a side elevation of Fig. 3;

Fig. 5 is a detail cross section on the line 5—5 of Fig. 3.

Fig. 6 is a front elevation of a modified form of the device in display position.

Fig. 7 is a plan of Fig. 6 also showing by dotted lines the position of the parts of the folder.

The sections 5, 6 and 7 of the folder respectively constitute the intermediate and opposite side sections and each is formed of fibrous material, such as pasteboard. In the folded position of the folder the side sec-

tions 6 and 7 are superimposed one upon the other and upon the intermediate section 5, to which the said side sections are fixedly secured in any suitable manner as by the staples 8 which pass through opposite marginal portions 9—10 of the intermediate section and through adjacent marginal portions 11—12 of the sections 6 and 7, and thereby hold the opposed faces of the said marginal portions in contact throughout. For the sake of neatness, the opposite side edges of the intermediate section adjacent to the staples 8 coincide with the adjacent side edges of the sections 6—7; and at least one of the latter is constructed narrower than the intermediate section in order to permit folding thereof upon one face of the intermediate section without interference from the secured marginal portion of the opposite section. At points between their free and secured sides and adjacent to the staples 8, the side sections are scored or crease-hinged as indicated by 13. By preference, the crease-hinges are disposed on the marginal portions 11—12 of the sections 6—7, so that when the said sections are turned outwardly to expose their front or display faces, and the front or display face of the intermediate section, the joint or space between the front faces and the front face of the intermediate section will be practically invisible to an observer positioned at a few feet distant from the display surface of the folder. This is of importance in that it is customary to print scenes or other matter for advertising purposes on the front face of the type of folder of this invention, and in instances where the printing on the display surface of each section is complementary to the printing on the display surfaces of the other sections a visible break or lack of continuity in the display surface invariably reduces the attractiveness of the same to no small extent.

When the device of this invention is not in use, the sections 6—7 are folded one upon the other and upon the intermediate section 5. In this position of the parts, the thickness of the folder corresponds to the combined thickness of the said sections, so that the folder occupies a minimum of space in shipment. In display position the sections 6—7 are turned on the crease-hinges 13 into angular relation to the section 5, and thereby cooperate with the latter and with one an-

other to support the folder upright on a suitable stand. In the modified form shown in Figs. 6 and 7, the intermediate section 15 and side sections 16 and 17 are connected 5 together so as to fold and unfold as described in connection with the form shown in Figs. 1 to 5 inclusive. In Fig. 7 it will be observed that the marginal portions 18-18 and the side sections 16 and 17 are 10 connected to opposite marginal portions 20-20 of the intermediate section 15. In this connection it will be observed that the staples 8 described in connection with Figs. 1 to 5 inclusive are omitted and eyelets 21 15 substituted therefor and the crease-hinges 22-22 are formed adjacent to the marginal portions 20-20 of the intermediate section 15 instead of being incorporated with the side sections 6 and 7 as shown in Figs. 1 20 and 5. What has been said in connection with the advantage had by the provision of the crease-hinges in the preferred form of the invention may be taken to apply to the construction of crease-hinge shown in the 25 modified form. It is to be understood that the folder of this invention may comprise any desired number of sections, and these may be constructed in various sizes, shapes or contours, according to the character of 30 advertisement to be displayed.

Although I have shown and described an ideal embodiment of the invention, it is to be understood that the same is susceptible of certain mechanical modifications the right 35 to the use of which is hereby proposed within the scope claimed.

I claim:

1. A display easel of the character described comprising a main panel centrally disposed and having marginal portions lying 40 in the same plane therewith, and a pair of laterally disposed side panels adapted to overlap one another at their free edges and to fold against said main panel when closed, 45 the outer portions of said lateral panels being provided with marginal portions lying substantially in the same planes with the respective lateral panels when the same are in the closed position but extending angularly thereto when said lateral panels are 50 opened, said lateral panels and their respective marginal portions having crease hinges

formed therebetween on which the lateral panels may fold into and out of closed position with respect to the main central panel, 55 said lateral panels when opened forming unbroken extension surfaces with the main central panel, and means passing through the marginal portions of the main panel and the marginal portions of said lateral panels for 60 securing the same rigidly together.

2. A display stand comprising a main panel located intermediately and having marginal edges which lie transversely in the same plane therewith and which are in the 65 same rigid piece and rigidly connected to the body of the main panel, lateral panels coöperating with said main panel and adapted to fold over upon the face thereof, said lateral panels having marginal portions in 70 one piece therewith but flexibly secured thereto and extending at an angle to the planes of the lateral panels when the latter are in open display position, said lateral panels and their marginal portions having 75 crease hinges formed therebetween on which the lateral panels may swing and which form unbroken surfaces with the central panel, and metallic fastenings passing directly through the marginal portions of said lateral panels and the marginal portions of 80 said central panel.

3. A display folder comprising panels foldably associated and adapted when extended to lie at substantially an obtuse angle 85 and being crease-hinged along an upright line, said panels having marginal portions adapted to overlap, the crease-hinge being formed at the overlapping marginal portions 90 and forming an unbroken surface between the panels for receiving a single composite display picture extending in part upon both panels and being completed by the two panels in association when in the opened position, and means going through 95 the overlapped marginal portions of the panels for securing the same together, said means being adjacent the crease-hinge for permanently holding the panels closely together therat.

In testimony that I claim the foregoing as my invention, I have signed my name hereunder.

FRANCIS X. LIST.
